DISPENSING CAN OR SIMILAR ARTICLE

Robert J. France and Karl T. Davis, Long Beach, Calif.,
assignors to Purex Corporation, Ltd., Lakewood, Calif.,
a corporation of California

Filed Sept. 1, 1964, Ser. No. 81,554

Term of patent 14 years

(Cl. D58—17)

FIG. 1.

FIG. 2.

FIG. 3.

FIG. 1 is a front elevational view of a dispensing can embodying our new design;

FIG. 2 is a side elevation of FIG. 1; and

FIG. 3 is a top plan view of FIG. 1.

The dominant features of my design reside in the portions shown in full lines.

We claim:

The ornamental design for a dispensing can or similar article, substantially as shown and described.
